United States Patent Office

Des. 204,716
Patented May 10, 1966

204,716

HUMIDIFIER

Warner W. Martin, Olmstead Falls, Ohio, assignor to The Lau Blower Company, Dayton, Ohio, a corporation of Ohio

Filed Sept. 13, 1965, Ser. No. 86,970

Term of patent 14 years

(Cl. D62—4)

FIG-1

FIG-6

FIG-7

FIG. 1 is a perspective view of a humidifier, showing my new design;

FIG. 2 is a side view of my new design;

FIG. 3 is another side view thereof;

FIG. 4 is a top view thereof;

FIG. 5 is a bottom view thereof;

FIG. 6 is an end view thereof; and

FIG. 7 is another end view thereof.

The dominant features of my design reside in the portions shown in full lines.

I claim:

The ornamental design for a humidifier, substantially as shown and described.
